WALTER M. CREITZ, OF BETHLEHEM, PENNSYLVANIA.

GUARD-RAIL STRUCTURE.

1,352,356.

Specification of Letters Patent. Patented Sept. 7, 1920.

Application filed June 14, 1920. Serial No. 388,902.

To all whom it may concern:

Be it known that I, WALTER M. CREITZ, a citizen of the United States of America, residing at Bethlehem, in the county of 5 Northampton and State of Pennsylvania, have invented new and useful Improvements in Guard-Rail Structures, of which the following is a specification.

This invention relates to railway or other 10 tracks of a similar nature and has for its object the provision of a track including guard rails adapted to be disposed adjacent but in spaced relation to the rectangular track rails at dangerous points such as bridge approaches, curves, and the like, the guard rail 15 extending higher than the track rails and being for the purpose of being engaged by the train wheels in case the train should jump the track, the space between the track rails 20 and the guard rails being filled with crushed stone for the purpose of reducing the speed of a train jumping a track.

Another object is the provision of a guard rail of this character which has associated 25 therewith brace members to which the guard rail is secured and the brace members being mounted upon alternating ties so as to produce a very strong structure.

With the above and other objects and advantages in view, the invention consists in 30 the details of construction to be hereinafter more fully described and claimed, and illustrated in the accompanying drawings in which

35 Figure 1 is a plan view of the track showing my guard rails in position,

Fig. 2 is a cross sectional view, and

Fig. 3 is a detail perspective of one of the brace members.

40 Referring more particularly to the drawings, the letter A designates the rails of an ordinary trackway which are of course secured upon the ordinary ties B. In carrying out my invention I provide guard rails 45 10 formed as channel irons and which are located at dangerous points, such as for example on a curve, as shown in Fig. 1, at the outer sides of the rail A and these channel irons 10 are located exactly the same distance apart as the rails A. Every alternate tie carries a brace designated by the numeral 50 11 and which includes a base portion 12 having holes 13 and further including an upright portion 14 with which is formed an

inclined web 15 also formed upon the base 55 portion 12 and serving as a brace. The upright portion 14 is also provided with holes 16. This brace structure is located on the alternate ties, as clearly shown, and the guard rails 10 are disposed upon the plates 60 12 and against the upright portions 14 and bolted to the latter, as shown at 17. The brace members are secured upon the ties by means of spikes 18 which pass through the holes 13. The guard rails 10 are of greater 65 height than the rails A, as clearly shown.

The space between the guard rails and the rails A is filled with crushed stone, as shown 70 at 19. In the event that a train should jump the track as for instance in going around a curve illustrated in Fig. 1, the wheels of the derailed truck or trucks after leaving the rails A will roll onto the crushed stone 19 whereupon the speed of the car or cars will naturally be checked. The wheels will then 75 strike against the guard rails 10 and the car or cars will consequently be prevented from turning turtle or plunging down an embankment or the like.

From the foregoing description and a 80 study of the drawings it will be apparent that I have thus provided a very simple and efficient track construction having guard rails which will positively prevent serious derailment of a car or cars and will therefore obviate one of the many dangers incidental to railroads.

While I have shown and described the preferred embodiment of my invention, it is of course to be understood that I reserve the 90 right to make such changes in the form, construction, and arrangement of parts as will not depart from the spirit of the invention or the scope of the subjoined claims.

Having thus described my invention, I 95 claim:

1. In combination with the rails of a trackway, guard rails secured upon the ties of the trackway at corresponding sides of the track rails and at the same distance apart as the 100 distance between the rails and projecting above the rails, and the spaces between the rails and said guard rails being filled with crushed stone, both the rails and also the guard rails extending above the crushed 105 stone.

2. In combination with the rails of a trackway, guard rails located at corresponding

sides of the track-rails and having the same gage as the track, and means for holding said guard rails in position comprising members carrying the guard rails and secured upon spaced ties of the trackway, each of said members including a plate portion

spiked upon the tie and further including an upright portion bolted to the guard rail and provided with an inclined web extending from the upright portion to the plate portion and formed integrally therewith.

In testimony whereof I affix my signature.

WALTER M. CREITZ.
